UNITED STATES PATENT OFFICE.

ARTHUR R. MOSLER, OF NEW YORK, N. Y., ASSIGNOR TO A. R. MOSLER & CO., OF NEW YORK, N. Y., A CORPORATION OF NEW YORK.

SEPARABLE SPARK-PLUG.

1,131,154.

Specification of Letters Patent.

Patented Mar. 9, 1915.

Application filed November 19, 1908. Serial No. 463,474.

To all whom it may concern:

Be it known that I, ARTHUR R. MOSLER, a citizen of the United States, and resident of the borough of Manhattan, in the city 5 and State of New York, have invented a new and useful Improvement in Separable Spark-Plugs, of which the following is a specification.

My invention relates to spark plugs and 10 has for one of its objects to provide a spark plug in which the shell is composed of separable sections, so that the plug may be very readily taken apart for cleaning, without unscrewing the shell from the cylinder wall.

15 Another object is to provide a spark plug in which the insulating block is spaced from the shell so as to insure a more perfect insulation.

20 A further object is to provide certain improvements in the construction, form and arrangement of the several parts whereby a more perfect ignition is obtained.

25 A practical embodiment of my invention is shown in the accompanying drawings in which,

Figure 1 is a side view of my spark plug screwed in position in a portion of the cylinder wall, Fig. 2 is a longitudinal central section of the same, Fig. 3 is a similar view 30 of the inner portion of the shell, Fig. 4 is a similar view of the remainder of the plug, Fig. 5 is a side view of the inner section of the shell, Fig. 6 is an inner end view of the inner section of the shell, Fig. 7 is an outer 35 end view of the same, and Fig. 8 is a detail view, partly in section, showing the manner in which the sparking point is pinched in the conducting wire.

The shell of the spark plug comprises the 40 inner section 1, the outer section or cap 2 and the intermediate section 3. The inner section is provided with cleaning holes 4, 5, through its inner end and side walls and its outer end is reduced, leaving the shoulder 6. 45 This reduced portion is exteriorly screw-threaded for engagement with the interiorly screw-threaded inner end of the intermediate section 3. The inner section is hollow and is provided with an enlarged chamber 6* near its outer end. The outer end of the intermediate section 3 is exteriorly screw-threaded for engagement with the interiorly screw-threaded outer section 2. The intermediate section 3 is further provided

with an interior annular flange 7 intermediate its ends.

The insulating block comprises the reduced end portions 8, 9, and the enlarged intermediate portion 10. This block is provided with a hole therethrough and the reduced end portion 8 has an enlarged recess 11 therein, at the bottom of which there is an angular recess 12. The inner end of the insulating block is spaced a distance from the holes 4, 5, thus forming a combustion 60 chamber within the plug for insuring the ignition of the main charge and the cleaning of the sparking point.

The conducting wire 13 passes through the insulating block and is screw-threaded 70 for a portion of its length. It is provided with a nut 14 thereon which fits the angular recess 12, so as to permit the conducting wire to be longitudinally adjusted by turning it in either direction. The outer end 75 of the conducting wire projects beyond the insulating block, and may be provided with the usual lock nut 15 and thumb nut 16. The inner end of the conducting wire is provided with a hole for the reception of the 80 sparking point 17, which point is secured in position by pinching the end of the conducting wire around said sparking point, as shown at 18. A small space is left between the inner end of the sparking point and the 85 bottom of the hole in the conducting wire for permitting the sparking point to expand as it is pinched. The pinching pressure is exerted at a point intermediate the ends of the sparking point, so that the inner end 90 of the same may remain at its normal size, thus anchoring the sparking point in place in the conducting wire, as shown in Fig. 8.

A packing ring 19 is disposed between the shoulder 6 on the inner section 1 of the shell 95 and the inner end of the intermediate section 3. A packing ring 20 is disposed between the outer end of the section 1, the reduced end portion 8 of the insulating block and the flange 7 on the intermediate section. 100 A packing ring 21 is disposed between the flange 7 and the enlarged intermediate portion 10 of the insulating block. A packing ring 22 is disposed between the outer end of the section 3, the enlarged portion 10 and 105 the outer section 2. All these packing rings serve to make the spark plug gas-tight and the rings 20, 21, 22, also serve to space the

insulating block from the shell so as to insure a perfect insulation. The packing rings 21, 22, also serve to hold the insulating block within the outer and intermediate sections 5 2, 3, when they are separated from the inner section 1.

The provision of the chamber 6* near the outer end of the inner portion of the shell is a very valuable feature, inasmuch as it 10 absolutely prevents short circuiting of the plug due to the collection of oil and soot between the insulating block and the shell. Its operation is as follows: Every time compression takes place in the cylinder in connection with which the plug is being used, the chamber 6* is filled with explosive vapor, and when explosion takes place, the combustion in the chamber 6* effectually clears the space between the insulating block and 15 20 the inner portion 1 of the shell, of any oil or soot.

By the construction hereinabove set forth, I obtain a separable spark plug the interior parts of which may be very easily taken out 25 for cleaning, without removing the inner section of the shell from the cylinder wall, thus entirely exposing the inner part of the insulating block and conducting wire while the same are still firmly held by the intermediate and outer sections of the shell. This 30 is a very valuable feature in practice. Furthermore, the plug is absolutely proof

against short circuiting resulting from the collection of oil or soot.

It is to be understood that I do not wish 35 to limit myself strictly to the form and construction herein set forth as many alterations may be made without departing from the spirit and scope of my invention.

What I claim is:

A spark plug comprising a shell composed of inner, outer and intermediate sections, said inner section having holes through its inner ends and side walls, said intermediate section having an interior annular flange intermediate its ends, a conducting wire and insulating block having reduced end portions and an enlarged intermediate portion, packing rings interposed between the enlarged intermediate portion of the block, the flange 45 and the outer section of the shell, for holding the insulating block independently of the inner section, and another packing ring interposed between the said flange and the outer end of the inner section of the shell. 50

In testimony, that I claim the foregoing as my invention, I have signed my name in presence of two witnesses, this twenty-second day of October 1908.

ARTHUR R. MOSLER.
